J. G. CLARK.
CRUDE OIL VAPORIZER AND BURNER.
APPLICATION FILED OCT. 21, 1910.

1,006,534.

Patented Oct. 24, 1911.

UNITED STATES PATENT OFFICE.

JAMES G. CLARK, OF VANCOUVER, BRITISH COLUMBIA, CANADA.

CRUDE-OIL VAPORIZER AND BURNER.

1,006,534.

Specification of Letters Patent. Patented Oct. 24, 1911.

Application filed October 21, 1910. Serial No. 588,832.

To all whom it may concern:

Be it known that I, JAMES G. CLARK, citizen of the Dominion of Canada, residing at Vancouver, in the Province of British Columbia, Canada, have invented a new and useful Crude-Oil Vaporizer and Burner, of which the following is a specification.

This invention relates to a crude oil vaporizer and burner and belongs to that class 10 wherein the vaporous fluid generated from the crude oil is intimately mixed before delivery to the burner with superheated steam, the generation of the vaporous fluid and the superheating of the steam being both effected 15 by the heat of the flame from the burner, and the invention comprises the particular method of construction and arrangement of the several parts whereby these objects are attained in a compact self contained device 20 and in an effective and satisfactory manner.

The invention is particularly described in the following specification, reference being made to the drawings by which it is accompanied, in which:

25 Figure 1 is a vertical longitudinal section through the device, Fig. 2, a cross section on the line A A looking in the direction of the arrow, Fig. 3, a cross section on the line B B looking in the direction of the arrow, and 30 Fig. 4, a longitudinal section of the mixer and burner detached.

In these drawings 2 represents a circular plate forming the front plate or base of the burner to which plate the several parts of 35 the casing, etc., are secured and by which the burner, as a whole, is attached to the front plate of the furnace or combustion chamber of a boiler or the like.

A hollow cylinder 2 having a closed end 5 40 in the center of which is an aperture 6 delivering the combined oil vapor and steam to the burner nozzle 7, is secured by any convenient means to the front plate 2 so as to form a closed cylindrical chamber 4. 45 Through the axial center of this chamber 4 is passed a control valve and mixing chamber which will be described later. Secured to the same front plate 2 so as to be concentric with the cylinder 3 is a cylindrical casing 20 leaving an annular space 21 through which the air for combustion at the burner is allowed to pass through apertures 26 in the front plate 2, and to enable this air for combustion to be well heated prior to delivery to the flame of the burner the casing 20 is carried beyond the end plate 5 to which

the burner nozzle 7 is secured and is doubled back, as at 22 to a position close to the end plate 5 leaving a space 27 between the inner end of 22 and 5 for delivery of the air to the 60 burner.

To insure that the entering air to support combustion is brought into close contact with the wall 22 of the casing next to the burner flame a cylindrical partition 23 is 65 seated at 24 on the end of the cylinder 3 and is carried forward toward the end of the casing 20 where it doubles around to 22 and against the doubled end projections 25 from the end of the partition 23 bear against 70 the inner end of the casing so that the partition 23 is held in place upon its seat 24.

A steam pipe 8 is inserted through the front plate 2 which pipe passes directly through the chamber 4 and within the casing projection 22 is formed into a coil, the end of it being conducted back from the inner coil and is passed through the end plate 5 at 10 into the chamber 4. Where these pipes pass through the end plate 5 80 they may be gland-packed in any suitable manner that the pipe may be free to expand and contract. An oil pipe 30 is passed also through the front plate 2 and is coiled within the chamber 4, the coil commencing at 85 the end farther from the front plate and passing through that plate to be connected at 31 to the pipe 11, which pipe is screwed at 14 on the outer end of the needle valve stem. The bushing 15 is screwed into the end of a casing tube 12 which is secured on the end 5 of the cylinder 3 and projects into close proximity with the end plate 2. The aperture 32 of the needle valve delivers into a 95 conical cavity 16 which is provided with a series of apertures by which the escaping crude oil vaporous fluid is diffused, and the outside of the bushing 15 where it is screwed into the tube 12 is furnished with a series of deep angled grooves 17 through which steam is delivered to mix with the diffused vaporous fluid. The inner side of the passage 6 through which the mixed vaporous 10 fluid and steam is delivered to the burner nozzle 7 is provided with a spiral groove 18 which aids in mixing the vaporous fluid and steam effectually together.

In operation the steam delivered at 8 is 110 superheated during its passage through the coil 8 before it is delivered into the chamber

4 through its proximity to the flame from the burner nozzle 7. The crude oil admitted at 30 to the coil within the steam filled chamber 4 is vaporized by the heat therefrom and the vapor is delivered at 31 into the pipe 11 from which it is admitted through the needle valve into the cavity of the diffusing cone 16. It is here mixed with the superheated steam from the chamber 4 which passes around the end of the casing pipe 12 and is delivered through the grooves 17 at an angle that will cause a circular motion favorable to efficient mixing, which circular motion is reversed as the vaporous mixture passes through 6 and in contact with the spiral grooves 18. As the mixture escapes through the burner nozzle 7 a supply of heated air which has been admitted at 26 and has been heated in its passage through the annular space 21 before delivery at 27 to the burner is furnished to the flame by which efficient combustion of the mixture is insured.

It will be obvious that if the burner is used for a purpose where steam is not available for delivery to the pipe 8 a small quantity of water may be admitted thereto which will become steam in its passage through the coil.

30 A steam connection 35 may be made by which in the event of the needle valve or burner nozzle becoming obstructed the same may be blown through in which use the crude oil supply will be closed by a valve external to the device or if found necessary the oil coil may also be blown through.

Having now particularly described my invention and the manner of its use, I hereby declare that what I claim as new and desire to be protected in by Letters Patent, is:

1. An oil vaporizer and burner, comprising in combination, a hollow cylinder from one end of which a burner nozzle projects, a fuel pipe passing through the cylinder and connected to the burner nozzle, an oil vaporizing pipe coiled within the cylinder one end of which pipe is connected to a source of oil supply, and the other to said first mentioned pipe, a steam generating pipe coiled in front of the burner nozzle and delivering into the hollow cylinder in which is the oil vaporizing coil, and means for admitting steam from the cylinder to mingle with the vapor before delivery to the burner nozzle.

2. An oil vaporizer and burner, comprising in combination, a hollow cylinder from one end of which a burner nozzle projects, a pipe passing through the cylinder and connected to the burner nozzle, an oil vaporizing pipe coiled within the cylinder one end of which pipe is connected to an oil supply source and the other to said first mentioned pipe, a steam generating pipe forming a coil around the burner nozzle and pro-

jecting beyond it, one end of which coil is connected to a supply source of water and the other end delivering into the hollow cylinder, means for admitting steam from the cylinder to mingle with the vapor before delivery to the burner nozzle, a casing encircling the steam cylinder and its generating coil, means for delivery of air to the annular space between the casing and the cylinder and means for delivering air from the casing adjacent to the burner nozzle.

3. An oil vaporizer and burner, comprising in combination, a hollow cylinder from one end of which a burner nozzle projects, a pipe passing through the cylinder and connected to the burner nozzle, an oil vaporizing pipe coiled within the cylinder, one end of which is connected to an oil supply and the other to said first mentioned pipe, a steam generating pipe coiled in proximity to the burner nozzle, one end of which pipe is connectible to a water supply and the other end delivering into the hollow cylinder, means for admitting steam from the cylinder to the burner, a casing encircling the steam cylinder and its oil vaporizing coil, said casing being projected beyond the cylinder and doubled back to a position adjacent to the end of the cylinder, and a cylindrical partition seated on the cylinder end and projected within that portion of the casing which projects beyond the cylinder.

4. An oil vaporizer and burner comprising in combination, a hollow cylinder having a burner nozzle projecting from one end and having a passage through the same, a tube extending from the burner nozzle backward toward the other end of the cylinder and in communication with the passage of the burner nozzle, a bushing within said tube, a fuel delivering pipe connected to said bushing, and a needle valve to control the passage of fuel to said nozzle, said bushing including a diffusing cone portion, said bushing having a peripheral angled groove in its bearing portion, means for delivering oil to the fuel delivering pipe and means for delivering steam into the hollow cylinder.

5. An oil vaporizer and burner comprising in combination, a closed hollow cylinder having an aperture in one end, a burner nozzle secured over said aperture on the outside of said cylinder, a tube extending from said aperture within the cylinder to a position adjacent to said other end, the wall surrounding the aperture in the cylinder end adjacent to the nozzle being provided with spiral grooves, a bushing within the tube adjacent to the nozzle and in contact with the walls of the tube, said bushing having peripheral angled grooves and having a passage through its center, said bushing including a hollow apertured cone on one side and in communication with said passage, a fuel delivering pipe connected to the bushing op-

- posite to said hollow cone, a needle valve controlling the passage through said bushing, an oil vaporizing coil within said hollow cylinder, one end of said coil being connected to an oil supply source and the other end being connected to said fuel delivery pipe, means for generating steam from the flame of the burner and delivering it to the cylinder within which the oil vaporizing tube is coiled, and means for heating the air for combustion before delivering it to the flame from the nozzle.
6. An oil vaporizer and burner, comprising in combination, a hollow cylinder having a front plate, said cylinder having a closed end with an axial passage therethrough to the outer end of which a burner nozzle is secured and the inner end of which is provided with a tube extending to adjacent to the front plate, an oil vaporizing coil within the cylinder, one end of which is connected to a source of oil supply and the other
- to a pipe delivering to the burner nozzle, a cylindrical partition concentric with and projecting beyond the end of the cylinder 25 in which is the burner nozzle, a cylindrical casing inclosing the cylinder and the cylindrical partition and carried around the latter to a position adjacent to the end of the cylinder, means for delivering air to the annular space inclosed by such casing, a steam generating coil within the projecting end of the casing, said coil delivering into the cylinder in which is the oil vaporizing coil, and means for mixing the vaporized oil 35 and steam before delivery to the burner nozzle.
- In testimony whereof I have signed my name to this specification in the presence of two subscribing witnesses.
